US00D914318S

(12) **United States Design Patent** (10) Patent No.: **US D914,318 S**
(45) Date of Patent: **** Mar. 23, 2021**

(54) **FRAME FOR A SHOPPING CART**

(71) Applicant: **Retail Design Services, LLC**,
Northfield, MN (US)

(72) Inventors: **John Robert Ebling**, Northfield, MN
(US); **Gary Robert Ebling**, Northfield,
MN (US)

(73) Assignee: **Retail Design Services, LLC**,
Northfield, MN (US)

(**) Term: **15 Years**

(21) Appl. No.: **29/699,442**

(22) Filed: **Jul. 25, 2019**

(51) LOC (13) Cl. **12-02**

(52) U.S. Cl.

USPC **D34/21**

(58) **Field of Classification Search**

(57) **CLAIM**

The ornamental design for a frame for a shopping cart, as shown and described.

DESCRIPTION

FIG. 1 is an isometric view of a frame for a shopping cart;
FIG. 2 is a side view thereof;
FIG. 3 is an isometric view thereof;
FIG. 4 is a front view thereof;
FIG. 5 is a rear view thereof;
FIG. 6 is a side view thereof as taken from the left side of FIG. 4;
FIG. 7 is a side view thereof as taken from the right side of FIG. 4;
FIG. 8 is a top view thereof; and,
FIG. 9 is a bottom view thereof.

The baskets shown in broken line in FIGS. 1 and 2 depict environment that form no part of the claimed design. All other broken lines in the figures are to show portions of the frame for a shopping cart which form no part of the claimed design.

1 Claim, 9 Drawing Sheets
